UNITED STATES PATENT OFFICE.

LEO A. MASCHMANN, OF ST. LOUIS, MISSOURI.

FOLDING LANDING NET.

Application filed August 16, 1922. Serial No. 582,253.

To all whom it may concern:

Be it known that I, LEO A. MASCHMANN, a citizen of the United States, residing in the city of St. Louis and State of Missouri, have invented certain new and useful Improvements in Folding Landing Nets, of which the following is a specification.

This invention relates to foldable or collapsible fishing nets, and is a distinct and practical improvement to overcome certain practical objection to, and defects in, the present universal types of landing nets.

The object of my present invention is to construct a net to be folded in one unit without dissembling its component parts, and, to reduce the volume of the net when collapsed to a minimum space to be carried with ease, or conveniently stored away in hand bags or the like.

A further object of my invention is to provide a simple and sufficient structural formation and combination of parts in a combined unit adapted for a ready and substantial connection.

Another object of this invention is to provide a device of the character indicated having novel means for adjustable sections from a central, or single point to shift the parts to their predetermined point.

With the above and other objects in view, the invention consists in the novel features of construction, arrangement and combination of parts hereinafter more fully described and finally pointed out in the claim hereto appended.

Referring to the accompanying drawings forming a part of this specification, wherein like characters of reference denote similar parts throughout the several views:

Fig. 1, is a plan view of the frame section embodying my invention.

Fig. 2, is a plan view of the hinged section of a rectilinear area.

Fig. 3, is a plan view of the hinged section in the wedge collar.

Fig. 4, is a plan view of the angular hinged section engaging the straight cross arms.

Fig. 5, is a plan view of a hinged terminal connection for the rectangular bar-arms.

Fig. 6, is a side view of the wedge collar and handle showing parts partly broken away.

Fig. 7, is a plan view of the net supporting frame-member in collapsed position.

Fig. 8, is a plan view of the frame mem-

bers and handle in collapsed position with the net fabric wrapped around the frame and handle thereof.

Fig. 9, is an assembled view of my device in perspective.

Fig. 10, is a bottom view, in perspective, of a bearing plate in the wedge collar showing the different recessed arrangement.

Referring to the drawing, the distended structure of my device is clearly shown in Figs. 1 and 9. The device is composed of a series of spaced frame members arranged at equal distances to swing about a fixed center in different angular adjustment for clamping purposes. The longitudinal co-acting rods 4 and 5 are hinged at their outer terminals 6 to the biforked sleeves 7 by means of the pins 8. The rods 4 and 5 also have a central hinged connection wherein the rod 4 is composed of a bearing sleeve 9 with flat extensions to overlie each other, said extensions comprising bifurcated terminals to engage the flattened end portion 10 of rod 5. The shoulder 11 on rod 5 formed by flattening the terminal portion of the rod 5 will limit the movement of the bearing sleeve 9 from its rectilinear position.

Mounted within the internal screw threaded portion of the bearing sleeves 7 are the adjacent rods 12 pivotally engaging the sleeves 13. Formed upon each sleeve 13 is a lip 14 to act as a stop to check the rods 12 against linear displacement. A rod 15 engages the internally screw threaded heel ends of one of the bearing sleeves 13 and has its oppositely disposed terminal fastened to a bearing sleeve 17, said sleeve 17 pivotally engaging a rod 16, as shown in Fig. 3. The sleeve 17 is formed at its junction with rods 15 and 16, with a bore 18 to detachably receive a thumb nut equipped bolt 20 passing through a wedge collar 19. Said wedge collar 19 is composed of a pair of jaws with their inner faces 21 and 22 in mutual contact with the bearing sleeve 17 and rod 16 and being provided with dogging devices 23 and 24; as shown in Figs. 6 and 10. Said dogging devices 23 and 24

are of a varied width so that when the component part of rod 16, the sleeve 17, in its angular travel will reach the dog 23 fitting the enlargement of the sleeve 17, it will normally lock said sleeve member 17 with its component rods 15 and 16 thereby

registering said rods in their longitudinal movement, and by clamping the jaws 21

and 22 of the wedge collar 19 with the thumb nut equipped bolt 20, the entire frame structure with its groups of aligned members will be held in rigid adjustment.

5 Integral with the upper jaw 21 of the wedge collar 19 is a circular frame portion 25 detachably engaging the handle member 26.

10 The reference numeral 27 represents a suitable net structure which is suspended from the frame members 4, 5, 12, 12, 15 and 16.

15 To convert the distended structure form of the above described fishing or landing net into a collapsible formation, the clamping bolt 20 is loosened sufficiently to disengage the jaws 21 and 22 from mutual contact with the bearing sleeve 17 and rod 16, thereby allowing all component parts to 20 disengage their hinged connection and be moved into a line of their length, as shown in Fig. 7. An inward turn of the upper jaw member 21, with its attached handle holder 25, will cause said handle member 25 and 25 handle 26 to overlie the collapsed frame portions, in linear alignment, as shown in Fig. 8, thus condensing the voluminous contents of the unit into an advantageous form for carrying purposes.

20 The many advantages of the herein described invention will readily suggest themselves to those skilled in the art to which it appertains.

I do not desire to be understood as limiting myself to the exact details of construction and arrangement as herein described and illustrated, as it is manifest that variations and modifications may be made without departing from the spirit and scope of my invention and the terms of the following claim, hence I wish it to be understood that I reserve the right to make any such changes, or modifications as may fairly fall within the scope of the appended claim when fairly construed.

45 What I claim is:

50 In a collapsible fishing net structure, a handle, a frame, said frame consisting of a pair of inner end members hingedly connected at their adjacent ends to said handle, a pair of outer end members hingedly connected at their adjacent ends, a pair of side members hingedly connected at their ends to said inner and said outer end members, 55 stops formed on the outer ends of the inner end frame members to hold the side members in parallel relation when the frame is in its open position, a net suspended from said frame members and means for clamping the adjacent hinged ends of the inner frame members against displacement for holding the frame in either rigid open position or rigid collapsed position.

60 In testimony whereof, I have hereunto signed my name to the specification.

LEO A. MASCHMANN.
